UNITED STATES PATENT OFFICE.

RAY P. HIGBEE, OF WILKINSBURG, PENNSYLVANIA, ASSIGNOR TO WESTINGHOUSE ELECTRIC & MANUFACTURING COMPANY, A CORPORATION OF PENNSYLVANIA.

ELEVATOR-CONTROL SYSTEM.

Application filed April 11, 1922. Serial No. 551,483.

To all whom it may concern:

Be it known that I, RAY P. HIGBEE, a citizen of the United States, and a resident of Wilkinsburg, in the county of Allegheny and State of Pennsylvania, have invented a new and useful Improvement in Elevator-
Control Systems, of which the following is a specification.

My invention relates to motor-control systems and it has particular relation to such systems of control as are employed in connection with elevators, hoists and similar machines.

One object of my invention is to provide means for controlling an elevator car or other device independently of the skill of the car operator, under predetermined conditions.

Another object of my invention is to eliminate devices located at the various floors to be mechanically operated by the car for certain control purposes.

A further object of my invention is to provide electromagnetic or similar means mounted on the car for controlling the car stops within predetermined limits of travel.

Other objects of my invention will be apparent from the following specification and appended claims.

It is common practice, in systems of elevator control, to provide switches in the hatchway that are operated by means of a cam attached to the car. Devices of this character have been employed to perform various functions, but are open to the objection that mechanical contact is necessary between the car and the stationary contact members.

I propose to eliminate mechanical connections between devices mounted on the car and other devices, of the above-indicated character, located external to the car. As an illustration of my invention, I provide an electromagnet, mounted on the car and arranged to energize an armature that may be located at any desired point of car travel in the hatchway. The armature is capable of movement and is arranged to operate electrical contact members without drawing the armature into contact with the electromagnet. A similar armature is preferably located adjacent to each landing.

In the arrangement that I propose for controlling an elevator motor, the magnet armature operates as a reversing switch to

perform the same functions as those normally required of the operator's car switch. When the operator attempts to stop at any floor or landing, the electromagnet becomes energized and actuates the magnet armature of the reversing switch to control the elevator motor independently of the operator and effect an accurate stop.

My invention will be described in connection with the accompanying drawing, in which the single figure is a diagrammatic view of circuits and apparatus embodying my invention.

A motor having an armature 1 and a field magnet winding 2 may be operatively connected, through reversing switches 3 and 4, to line conductors 5 and 6. An accelerating resistor 7 and a switch 8 are provided for controlling the motor. A brake 9 of any suitable and well-known form may be employed for mechanically controlling the rotation of the armature 1 and should be arranged to release the armature 1 upon closure of either of the reversing switches 3 and 4, in accordance with a familiar practice. The armature 1 may be operatively connected, in any desired manner, to a car 10 on which is located an operator's controlling switch or car-switch 11. An electromagnet 12 is mounted on the car. An armature or auxiliary reversing switch 13 of magnetic material, which is located adjacent to each landing, is pivotally mounted and maintained in its normal position by means of a spring 14. The armature 13 is influenced by the electromagnet 12, when the car-switch 11 occupies its inoperative or "off" position, to selectively engage contact members 15 and 16 for operating reversing switch 3 or reversing switch 4.

It may be assumed that the elevator car 10 is at rest and that the various switches and controlling devices occupy their inoperative or illustrated positions. When the car switch 11 is actuated for upward movement of the car 10, a circuit is established for the operating coil of switch 3 that extends from line conductor 6 through the operating coil of switch 3, conductor 17, contact member 18, car switch contact segment 19, contact member 21, and conductors 22 and 23 to line conductor 5.

Switch 3 thereupon closes to complete a circuit for the motor armature 1 that extends from line conductor 6 through switch 110

3, conductor 24, armature 1, resistor 7, and switch 3 to line conductor 5. The armature 1 accelerates, and starting resistor 7 is then excluded from the armature circuit by 5 means of switch 8, the operating coil of which is connected across the terminals of the armature 1. This method of controlling a motor is well understood and need not be further described. Moreover, any 10 other suitable method may be employed.

When the car switch 11 is returned to its "off" position, upon approaching a landing, contact segment 19 is disengaged from contact member 18 to interrupt the circuit 15 previously traced through the operating coil of the switch 3. A circuit for the operating coils of the electromagnet 12 is established from the line conductor 6 through conductor 25, operating coils of electromagnet 12, conductor 26, contact members 27 and 21, and conductors 22 and 23 to line conductor 5.

Assuming that the car 10 tends to stop below the level of the landing, the electromagnet 12 will energize and unbalance the armature 13, causing the latter to engage contact member 15. The electromagnet 12 is so located that a permanent air gap is maintained when armature 13 is in engagement with contact member 15. There is, therefore, no mechanical connection between the electromagnet and its armature. It will be noted that contact members 13 and 15 are electrically connected to contact members 21 and 18, respectively, for maintaining a circuit for the operating coil of switch 3 when the car switch 11 is in its "off" position.

When the car 10 attains the level of the desired landing, the armature 13 at that landing is restored to its normal or illustrated position, since the electromagnet 12 then exerts a magnetic pull upon each end of the armature 13. The latter being pivotally mounted, assumes its normal position, because of the balancing effects of the magnet upon its armature. The separation of contact members 18 and 15 interrupts the circuit previously traced through the operating coil of switch 3.

It will be apparent that if the car 10 tends to stop above the desired landing, the electromagnet 12 will influence the armature 13 oppositely, so as to establish a circuit 45 through contact member 16. This energizing circuit for the operating coil of switch 4 is established from line conductor 6 through the operating coil of switch 4, conductor 28, contact members 16 and 18, and conductors 29 and 23 to line conductor 5. Switch 4 closes to effect the operation of the car 10 in the downward direction until the car assumes a position substantially level with the desired landing, whereupon the 60 armature or contact member 13 is actuated

to its normal or inoperative position, as previously described.

It is evident that the car switch 11 may be actuated to the "down" position in the usual manner when it is desired to effect 70 the closure of switch 4 and the operation of the car 10 to any of the lower landings. It should be noted that, in its running positions, the car switch interrupts the operating circuit through the coils of magnet 12, 75 since contact members 19 and 27 are disengaged.

It will be understood that, while I have illustrated only a single armature and reversing contact members associated therewith, a similar armature, and contact members, connected in parallel relation to the illustrated contact members, should be located at any floor where it is desired to obtain automatic control of the elevator car. 80 85

I have thus shown a system that provides means for controlling the operation of a car or similar device within predetermined limits of travel, with respect to any landing, independently of the skill of the car 90 operator. I have eliminated mechanical contact, between the car and the operating switches, which in the past has been a source of considerable trouble, principally on account of the fact that the switches are easily 95 deranged. My invention further eliminates objectionable noise caused by the engagement of mechanically operated members.

I claim as my invention:

1. The combination with a car and a motor therefor, of a pair of magnetic members, one movable in accordance with movements of the car and the other adjacent to the path of said movable member, and a coil for energizing said members to control the motor. 100 105

2. The combination with a car and a motor therefor, of means carried by the car and also adjacent thereto and co-operating magnetically for controlling the direction of rotation of the motor. 110

3. The combination with a car and a motor therefor, of electromagnetic reversing means for the motor, a portion only of the magnetic circuit of said means being mounted on the car. 115

4. The combination with a car and a motor therefor, of a reversing switch for the motor and an electromagnet having part of its magnetic circuit on the car and part adjacent thereto for actuating the reversing switch. 120

5. The combination with a car and a motor therefor, of a reversing switch for the motor, an electromagnet on the car and an armature for the magnet adjacent to said car for actuating the reversing switch, and means for energizing said electromagnet. 125

6. The combination with a car and a motor therefor, of a reversing switch for the motor, an electromagnet on the car and an 130

armature for the magnet adjacent to said car for actuating the reversing switch, and a switch for controlling said electromagnet.

7. The combination with a car and a motor therefor, of a reversing switch for the motor, an electromagnet on the car and an armature for the magnet adjacent to said car for actuating the reversing switch, and a switch on the car for controlling said electromagnet.

8. The combination with a car and a motor therefor, of a car switch for controlling the motor, a reversing switch external to the car, and an electromagnet on the car controlled by the car switch, said switches and electromagnet being mechanically independent.

9. The combination with an elevator car and a hoisting motor therefor, of a car switch on the car, an electromagnet on said car energized when the car switch is in its "off" position, and a switch in the hatchway controlled by said electromagnet.

10. The combination with an elevator car and a hoisting motor therefor, of a car switch on the car, an electromagnet on said car energized when the car switch is in its "off" position, and a switch in the hatchway controlled by said electromagnet for controlling the motor.

11. The combination with an elevator car and a hoisting motor therefor, of a car switch on the car, an electromagnet on said car energized when the car switch is in its "off" position, and a switch in the hatchway controlled by said electromagnet for controlling the direction of rotation of the motor.

12. The combination with an elevator car and a hoisting motor therefor, of a car switch on the car, an electromagnet on said car energized when the car switch is in its "off" position and a reversing-switch in the hatchway controlled by said electromagnet for controlling the motor in accordance with the position of said car.

13. The combination with an elevator car and a hoisting motor therefor, of a car switch on the car, an electromagnet on said car energized when the car switch is in its "off" position, and a reversing-switch in the hatchway controlled by said electromagnet for controlling the car independently of the skill of the car operator.

14. The combination with an elevator car and a hoisting motor therefor, of a car switch on the car, an electromagnet on said car energized when the car switch is in its "off" position and a reversing-switch in the hatchway, at each floor, controlled by said electromagnet for controlling the car to effect accurate landings whether the car overtravels or undertravels with respect to any landing.

15. The combination with an elevator car and a hoisting motor therefor, of a car

switch on the car, an electroresponsive master switch controlled magnetically by said car and an electromagnetic reversing-switch controlled by either of said switches for controlling said car.

16. An electric elevator having, in combination, a cage, a hoisting motor for driving said cage, means for controlling the operation of said motor, and electromagnetic means for instituting a levelling operation of said motor only when said first mentioned means is in its inoperative position.

17. An electric elevator having, in combination, a cage, a motor for driving said cage, and a levelling device for controlling the operation of said motor, said levelling device comprising an electromagnet, a supporting frame for said electromagnet, a switch, and means under the influence of said electromagnet for operating said switch.

18. An electric elevator having, in combination, a cage, a motor for driving said cage, and electromagnetic means for instituting a levelling operation of the motor just before stopping said cage at a landing.

19. An electric elevator having, in combination, a cage, a motor for driving said cage, a switch device for controlling the operation of said motor, an electromagnetic means for producing an automatic levelling operation of said motor, said switch device acting to place said means into operative connection with said motor.

20. An electric elevator having, in combination, a cage, a motor for driving said cage, and electromagnetic means for causing an automatic levelling of said cage when a landing is to be effected.

21. An electric elevator having, in combination, a hatchway, a cage within said hatchway, stationary means mounted in said hatchway, and means supported by said cage for movement therewith, both mentioned means co-operating electromagnetically to effect a levelling operation of said motor.

22. In an electric elevator, in combination with a hatchway, a cage, and levelling means for governing the travel of said cage in said hatchway, said levelling means comprising a part secured to said hatchway and a part secured to said cage, said parts co-operating with each other without coming into mechanical engagement.

23. An electric elevator comprising, in combination, a cage, a motor for driving said cage, means for automatically controlling the operation of said motor, said means comprising a switch, a lever operating to actuate said switch, and magnetic means for effecting the movement of said lever without making mechanical connection therewith.

24. An electric elevator having, in combination with a hatchway, a cage moving

- therein and a driving motor for the cage, means for manually controlling the motor, and automatic levelling means arranged to operate said motor independently of said manual means, said levelling means comprising magnetically operated devices mounted partly on said cage and partly on said hatchway.
25. A levelling device for elevators comprising, in combination, a series of spaced magnetic elements mounted along the hatchway, and means mounted on the elevator cage and arranged to coact with said elements and act by magnetism to control said levelling means.
- 10 26. An elevator having, in combination, a cage, a motor for driving said cage, means for controlling the operation of said motor,

a magnetizable member secured in the elevator hatchway, and electromagnetic means 20 for co-operating with said member to effect a levelling operation of the motor

27. An elevator having, in combination, with a hatchway, a cage, means for driving said cage, a magnetizable member, and electromagnetic means for co-operating with 25 said member to effect a levelling operation of said driving means, said magnetizable member and said electromagnetic means being supported by said cage and said 30 hatchway for relative movement.

In testimony whereof, I have hereunto subscribed my name this 7th day of April, 1922.

RAY P. HIGBEE.
